(57) **CLAIM**

The ornamental design for a mobile robot, as shown and described.

DESCRIPTION

FIG. 1 is a front perspective view of a mobile robot, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a reference view showing a use state of the mobile robot wherein the display of the header of the mobile robot is erected; and,

FIG. 9 is a reference view showing a use state of the mobile robot wherein the wheel is covered by the body of the mobile robot.

The broken lines illustrating portions of the mobile robot form no part of the claimed design.

1 Claim, 6 Drawing Sheets
